CASE FOR BATTERY POWERED IN-LINE
ORTHOPEDIC SURGICAL CUTTING TOOL

Meyer Fishbein, 12020 Saltair Place,
Los Angeles, Calif. 90049

Filed Sept. 7, 1971, Ser. No. 178,543

Term of patent 14 years

Int. Cl. D24—02

U.S. Cl. D83—12 R

FIG. 1 is a perspective view of a case for a battery powered in-line orthopedic surgical cutting tool showing my new design;

FIG. 2 is a side elevational view thereof looking in the direction of the arrow 2 in FIG. 1;

FIG. 3 is a side elevational view thereof looking in the direction of arrow 3 in FIG. 2;

FIG. 4 is a top plan view thereof; and

FIG. 5 is a bottom plan view thereof.

I claim:

The ornamental design for a case for battery powered in-line orthopedic surgical cutting tool, substantially as shown and described.
